US00D826166S

(12) **United States Design Patent** (10) **Patent No.:** **US D826,166 S**
(45) **Date of Patent:** **** Aug. 21, 2018**

(54) **ELECTRICAL CONNECTOR**

(71) Applicant: **DAI-ICHI SEIKO CO., LTD.**,
Kyoto-shi (JP)

(72) Inventor: **Tadamichi Yayoshi**, Machida (JP)

(73) Assignee: **DAI-ICHI SEIKO CO., LTD.**,
Kyoto-shi (JP)

(**) Term: **15 Years**

(21) Appl. No.: **29/595,723**

(22) Filed: **Mar. 1, 2017**

(30) **Foreign Application Priority Data**

Sep. 7, 2016 (JP) 2016-019338

(51) **LOC (11) Cl.** **13-03**

(57) **CLAIM**

The ornamental design for an electrical connector, as shown
and described.

DESCRIPTION

FIG. 1 is a front elevational view of an electrical connector;
FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front, top, and left side perspective view thereof;

FIG. 8 is a front, bottom, and right side perspective view
thereof;

FIG. 9 is an enlarged cross-sectional view along the line 9-9
in FIG. 1;

FIG. 10 is a cross-sectional view along the line 10-10 in FIG.
1;

FIG. 11 is a cross-sectional view along the line 11-11 in FIG.
3; and,

FIG. 12 is an enlarged view showing a portion of FIG. 11
defined by line 12-12.

The broken lines in the drawings illustrate subject matter
that forms no part of the claimed design.

1 Claim, 12 Drawing Sheets
